SHORT WAVE ANTENNA SYSTEM

Andrew Alford, San Mateo, Calif., assignor to
 Mackay Radio & Telegraph Company, New
 York, N. Y., a corporation of Delaware

Application March 15, 1938, Serial No. 195,946

4 Claims. (Cl. 250—33)

The present invention relates to antenna systems, and especially to short wave antenna systems of the tuned antenna type. The invention is particularly applicable to systems for use with short wavelengths, for example, wavelengths in the range of from 5 meters to 60 meters.

It is an object of the present invention to provide an antenna system of unusually compact form and small dimension. More particularly, it is an object to provide an unusually compact directive antenna system of the dipole type, which shall be small enough to render it convenient to rotate the complete antenna with approximately the same convenience as a loop antenna.

It is a further object of my invention to provide an antenna system of simple design which is readily adjustable for use at a number of different frequency ranges, and especially to provide such an antenna system in which the necessary adjustments in changing from one frequency to another in the same general range or in changing from one frequency range to another frequency range, can be effected in a particularly convenient manner.

It is a particular object of my invention to provide a compact, readily adjustable antenna system whose overall efficiency is substantially as high as that of a larger antenna system.

In accordance with my invention, compactness is attained in a short wave antenna without any substantial sacrifice of efficiency.

In accordance with a further feature of my invention, the antenna system is rendered operative for a relatively wide range of frequencies by providing an adjustable tuning circuit of the transmission line type, while at the same time convenience in effecting small frequency adjustments of the antenna is attained by further providing a trimmer condenser connected in shunt with the antenna. The resonant transmission line which is used to tune the antenna in accordance with my invention not only provides the above mentioned advantage of rendering the antenna semi-universal in respect to its frequency range, but also provides a very low loss resonant circuit immediately associated with the antenna, so that the reduction of antenna dimensions may be carried beyond the usual limit without substantial reduction of overall efficiency.

Although antennae which are only a small fraction of a wavelength long have been used for reception of long waves, such dimensions have only been employed because of the prohibitive cost of providing antennae of adequate length for

these long waves. In such cases the efficiency of the radiating or collecting system is greatly reduced by the low radiation resistance of such a short antenna. It has therefore come to be a generally accepted rule that an antenna whose length is only a small fraction of a wavelength must inherently result in a low efficiency of radiation or collection of energy.

In accordance with my invention, however, in short wave systems the antennae may be shortened to a very small fraction of a wavelength without a corresponding decrease in collecting or radiating efficiency.

A careful analysis of the factors which cause the reduction of efficiency when the radiation resistance of an antenna is reduced, indicates that this reduction of efficiency results from the fact that the radiation resistance of the antenna becomes comparable with or smaller than the effective resistance resulting from other factors, such as heat losses in the antenna itself, and especially power losses resulting from circulatory currents in the tuned system immediately associated with the antenna.

In accordance with my invention, therefore, a very small dipole antenna is immediately associated with a tuned circuit constituted wholly or principally by a Lecher wire system, or transmission line type of resonant circuit, which has a very low loss. The use of such a very low loss circuit immediately associated with the antenna does not in itself produce a substantial increase in efficiency with antennae of normal dimension, but the use of such a low loss circuit does very greatly reduce the minimum dimensional limit below which the antenna length cannot be reduced without substantial reduction of efficiency. By the use of a very low loss resonance circuit of the transmission line type immediately associated with a radiating or receiving antenna, I have found that the overall antenna length can be reduced to a very small fraction of a wavelength, for example, to one-tenth of a wavelength or less, without any substantial reduction of efficiency.

The exact nature of my invention can best be understood by reference to the attached drawing, in which

Fig. 1 represents a portable receiving system in accordance with my invention, and

Fig. 2 represents a portable directional receiving system in accordance with my invention.

Referring more particularly to Fig. 1, 1 and 2 are a pair of conductors disposed on a common axis so as to constitute a dipole. An open-wire

45

55

transmission line 3 provided with an adjustable short circuiting bar 4, is directly connected to the conductors 1 and 2, and serves as a "loading" impedance for tuning the dipole antenna to resonance. The length L of each of the dipole conductors 1 and 2 is a very small fraction of a wavelength, preferably between one-fifteenth and one-thirtieth of a wavelength. The impedance of the dipole is therefore predominantly capacitative and is, moreover, comparatively high, although the resistive component of the dipole impedance is exceptionally low. For an antenna of one-tenth wave-length overall dimensions (i. e. where L is somewhat lower than 0.05 λ) for short waves of the order of 15 to 30 meters, the effective resistance component of the dipole is approximately 2 ohms, most of this effective resistance being constituted by the radiation resistance of the dipole. The reactive component of the dipole impedance, however, is very much higher, being of the same order as the capacitative reactance of a section of open-ended transmission line L units in length.

In order to tune the dipole to resonance by neutralizing the capacitative reactance without introducing further resistive components of comparable magnitude to the radiation resistance, the necessary "loading" inductance is provided by that section of transmission line 3 which extends between the dipole and the short circuiting bar 4. The length H of this section of transmission line is adjusted by moving short circuiting bar 4 so that for the frequency to be received, or radiated, this short circuited section of transmission line as modified by certain further equipment connected thereto will present an inductive reactance equal to the capacitative reactance of the dipole antenna. Since the capacitative reactance of the dipole is roughly the same as the capacitative reactance of an open-ended section of transmission line of length L, the length H of the short circuited loop of transmission line will be roughly one-quarter λ minus L if the effect of the further equipment associated with this loop is small.

A receiver 7 is connected to one end of transmission line 5, and the other end of this line is adjustably clamped to a suitable point along the resonating section of transmission line 3, the point at which transmission line 5 is clamped to transmission line 3 being adjusted so as to approximately match the impedances at this point of junction. If the receiver impedance as viewed over line 5 from the junction is of a reasonable order of magnitude, the junction of the lines will then be much closer to short circuiting bar 4 than to the antenna. In practice this will be true with any ordinary receiver, if the line 5 is a negligible fraction of a wavelength long. If this line 5 is of considerable length, further matching means may be provided so that the surge impedance of this line may be accurately matched to the receiver as well as being matched at its junction with transmission line 3, but ordinarily the arrangement shown is adequate without further matching means.

A variable condenser 6 of small capacity is connected across transmission line 3, either at a small distance from the dipole or directly across the dipole antenna. In order to preserve symmetry it is preferred to make condenser 6 of the split stator type having two insulated stators and a common rotor; this is particularly desirable when the condenser is connected directly across the dipole. When the condenser is connected

across the transmission line 3, it is preferred that this condenser should be bridged across this transmission line at a point sufficiently close to the dipole antenna so as not to interfere with the adjustment of the connecting clamps of transmission line 5.

In case a slightly higher efficiency is desirable even at the expense of sacrificing convenience, the condenser 6 may be omitted and the tuning performed solely by adjustment of the short circuiting bar 4. Since the movement of short circuiting bar 4 varies the matching conditions of transmission line 5 to a considerable extent, it will ordinarily be necessary to readjust the point of clamping of transmission line 5 whenever the short circuiting bar 4 is moved by any considerable amount. If the condenser 6 is provided, however, a considerable adjustment of the frequency may be made by varying this condenser without greatly upsetting the matching adjustment of transmission line 5. Therefore, it is ordinarily preferred to provide the condenser as mentioned, and in this case the short circuiting bar 4 is only readjusted when changing from one frequency range to another frequency range, where as small changes between different frequencies in the same frequency range are effected by adjustment of condenser 6 without necessitating movement of the short circuiting bar 4 of the transmission line 5.

An antenna of the type described and illustrated in Fig. 1 is particularly useful for portable sending or receiving systems operating on wavelengths between 15 and 30 meters, since for this commercial range of wavelengths the dipole antenna of the usual type is so unwieldy as to be impracticable for portable use, whereas a dipole antenna system constructed in accordance with the present invention is sufficiently small to be readily portable. For a wavelength of 20 meters, for example, the dipole antenna of my invention may have an overall length of about six feet or less, while still presenting an efficiency which is only about one and one-third decibels below the theoretical maximum. Since there is some loss even in the case of an antenna several wavelengths long, it is clear that the reduction in efficiency of my antenna system by virtue of its very great reduction in length is for all practical purposes negligible.

A receiving system constructed in accordance with my invention and having an overall antenna length of less than 0.1 wavelength, has an average radiation efficiency in all directions which in spite of its minute size is substantially as great as that of the largest, most efficient system which could be theoretically imagined. This means that except for possible gains in efficiency in one direction which may be obtained in certain systems by corresponding reduction of efficiency in other directions, the small antenna of my invention will deliver to its receiver about as much power as any possible system regardless of size. In fact, the power delivered to the receiver by a system according to my invention is less than two decibels below the theoretical maximum. Similarly if my invention is used for a transmitting system the power radiated into the ether for a given number of watts supplied from the transmitter will be substantially as great as the power radiated from the largest, most efficient antenna system which could be designed. It will be clear, therefore, that the system of my invention is not comparable, except in size, with the inefficient "probe" antennae" or "exploring

rods" previously used for laboratory and field tests, but is rather to be compared with the much larger antennae having lengths of one-quarter λ , one-half λ and more, which have hitherto been used in all cases where an efficient radiation or collection of energy was required.

In accordance with a further feature of my invention, a very compact and readily portable direction finding system is provided as shown in Fig. 2. Referring more particularly to this figure, in which similar reference characters represent the same elements as in Fig. 1, the transmission line 3 and short circuiting bar, as well as the transmission line 5 and receiver 7, may be exactly the same as in Fig. 1. Instead of a single dipole consisting of two conductors 1 and 2, as in Fig. 1, the direction finding system of Fig. 2 comprises two dipoles parallel to one another and preferably vertically disposed as shown. One of these dipoles consists of the two conductors 1a and 2a connected to the transmission line 3 by the branch line 3a. The other dipole is exactly similar, consisting of two conductors 1b and 2b connected to the transmission line 3 by the branch line 3b. In accordance with my invention, not only is the length of each of these dipoles a very small fraction of a wavelength, but also the separation between the two dipoles is made a very small fraction of a wavelength. As shown in Fig. 2, the overall length of each dipole may, for example, be one-tenth λ , and the separation between the dipoles may also be one-tenth λ . Even smaller dimensions may be used without excessive reduction in efficiency.

It is preferred, in practising my invention, to maintain the length L of each half-dipole between 0.06 λ and 0.03 λ in both the system of Fig. 1 and that of Fig. 2, for most applications of the invention, where the wavelengths used lie within the ordinary commercial band. In the direction finding system of Fig. 2, the condenser 6 may be omitted just as in the system of Fig. 1, although it is preferred to provide this condenser for convenience in making small tuning changes between frequencies of the same general value as previously explained.

The system of Fig. 2 may be used either as a direction finder or as a directional transmitter. Similarly the system of Fig. 1 may be used either as a receiver or a transmitter. When the systems are used as transmitters, it is merely necessary to replace the receivers 7 by transmitters of corresponding impedance and frequency, and to construct the antenna and transmission line components with sufficiently strong insulation to withstand a higher voltage.

Both the system of Fig. 1 and the system of Fig. 2 are sufficiently compact so that the an-

tennae may be mounted on poles carried in the hand or on a motor vehicle, for making observation of field strength and other field observations.

Although certain embodiments of my invention have been described for the purposes of illustration, it will be understood that modifications, adaptations and variations thereof occurring to one skilled in the art, may be made within the scope of my invention as defined by the appended claims.

What I claim is:

1. A short wave antenna system of small dimensions which comprises a dipole antenna having an overall length of the order of one-tenth of the wavelength to be employed, a low loss circuit of the transmission line type directly connected to said dipole antenna the combination thereof being resonant at said wavelength, and a wave translating apparatus coupled to said low loss line.

2. A directive short wave antenna system comprising a dipole antenna whose overall length is of the order of one-tenth of the wavelength to be employed, a second similar dipole antenna disposed parallel to said first antenna and spaced therefrom by a distance of the order of one-tenth of the wavelength to be employed, a low loss reactive circuit comprising a transmission line connected to tune said two dipole antennae to resonance at the said wavelength, said line being differentially connected to said two dipole antennae so as to neutralize radiant action in a direction perpendicular to the common plane of said two dipole antennae, and means for coupling a wave translating device to a point on said transmission line.

3. A system according to claim 1, further comprising means for adjusting the effective length of said transmission line for tuning the system to different frequency ranges, and a variable condenser connected across said line adjacent the connection to said dipole for tuning the system to different frequencies in the same general frequency range.

4. A system for radiant action at wavelengths of the order of 15 to 30 meters, which comprises two antenna conductors each having a length between 0.06 λ and 0.03 λ , a low loss tuning transmission line connected at one end to said two conductors and effectively short circuited at an adjustable intermediate point to form a resonant circuit with said two conductors, a wave translating device, a second transmission line, means for coupling said device to said second line, and means for coupling said second line to said tuning line in impedance matched fashion.

ANDREW ALFORD.
